DECK CHAIR

Ralph A. O'Neill, Englewood, N. J.

Application August 12, 1950, Serial No. 11,740

Term of patent 14 years

(Cl. D15—1)

To all whom it may concern:

Be it known, that I, Ralph A. O'Neill, a citizen of the United States, residing at Englewood, Bergen County, State of New Jersey, have invented a new, original, and ornamental Design for a Deck Chair, of which the following is a specification, reference being had to the accompanying drawing, forming a part hereof.

Figure I is a perspective view of a deck chair, showing my new design; and

I claim:

The ornamental design for a deck chair, as shown.

RALPH A. O'NEILL.
